UNITED STATES PATENT OFFICE.

GRACE G. DRAYTON, OF NEW YORK, N. Y.

DESIGN FOR A BUNNY-DOLL.

44,885.

Specification for Design.

Patented Nov. 18, 1913.

Application filed September 10, 1913. Serial No. 789,180. Term of patent 3½ years.

To all whom it may concern:

Be it known that I, GRACE G. DRAYTON, a citizen of the United States, residing at New York, in the county of New York and State of New York, have invented a new, original, and ornamental Design for Bunny-Dolls, of which the following is a specification, reference being had to the accompanying drawings, forming a part thereof, and in which—

Figure 1 is a front view, and Fig. 2 is a

rear view of a bunny doll showing my new design.

I claim—

The ornamental design for a bunny doll, as shown.

GRACE G. DRAYTON.
